(57) **CLAIM**

The ornamental design for a candy mold, as shown and described.

DESCRIPTION

FIG. 1 is a front, top, left perspective view of a candy mold; FIG. 2 is a front view of a candy mold;

FIG. 3 is a rear view of a candy mold;

FIG. 4 is a top view of a candy mold;

FIG. 5 is a bottom view of a candy mold;

FIG. 6 is a left-side view of a candy mold;

FIG. 7 is a right-side of a candy mold;

FIG. 8 is a detail view of a front view of a candy mold as indicated in FIG. 2;

FIG. 9 is a detail view of a rear view of a candy mold as indicated in FIG. 3;

FIG. 10 is a bottom, cross-sectional, detail view of a candy mold along line 10 shown in FIG. 8;

FIG. 11 is a top, cross-sectional, detail view of a candy mold along line 11 shown in FIG. 8;

FIG. 12 is a right-side, cross-sectional, detail view of a candy mold along line 12 shown in FIG. 8;

FIG. 13 is a left-side, cross-sectional, detail view of a candy mold along line 13 shown in FIG. 8;

FIG. 14 is a bottom, cross-sectional, detail view of a candy mold along line 14 shown in FIG. 8; and,

FIG. 15 is a top, detail view of a candy mold as indicated in FIG. 4.

Any shading and cross-hatching are not features of the design but are utilized to illustrate the surface contours of the candy mold design in the drawings. The dash-dash broken lines depict portions of the candy mold that form no part of the claimed design. The dash-and-long-dash broken lines in

(Continued)

FIG. 4 indicate the detail view shown in FIG. 15, which also includes the dash-and-long-dash lines.
